UNITED STATES PATENT OFFICE.

WILLARD W. THOMPSON, OF DORCHESTER, MASSACHUSETTS, ASSIGNOR, BY MESNE ASSIGNMENTS, TO HOLOPHANE COMPANY, INC., OF NEW YORK, N. Y., A CORPORATION OF NEW YORK.

ILLUMINATING APPLIANCE.

Application filed July 16, 1923. Serial No. 651,838.

The object of my invention is the construction of an illuminating appliance preferably for use in the sick room of a hospital. The fixture is constructed to give a well-distributed, cheerful light of normal intensity, and also has a second source of illumination of low intensity to be used when the normal light is not desired. The unit has a low surface brilliancy and is free from shadows and distortions when either the normal or low intensity lamps are burning.

Figure 1 is a vertical cross section of an illuminating appliance embodying the features of my invention.

Figure 2 is a cross-sectional view of the preferred form of the socket cover employed in the device.

In the figure, 1 is the appliance, in which 2 is the canopy, preferably smooth and free from convolutions. 3 is a pipe or stem and 4 is a holder fitted directly into the stem and adapted to support a glass enclosure 5, which enclosure is of diffusing glass and preferably completely encloses the source 25 of illumination 6. This light source comprises a pipe or stem 7 which is threaded at its upper end to the upper pipe 3 by means of a coupling 8 and the lower end of stem 7 is also threaded to a smooth flaring socket 30 cover 9 containing receptacles for three lamps. The socket cover 9 is provided with a bottom plate 14 containing a large central aperture 15 and smaller apertures 16. Socket cover 9 is also provided with two 35 socket supporting brackets 18 which are integral with bottom plate 14. The upstanding walls of brackets 18 are drilled and tapped to receive screws 19 which act to secure the bottom plate to the socket cover. 40 Screws 17 are employed to secure socket 11 to the bottom plate 14 through holes 17. A central lamp 10 of usual voltage, say of 75 watts, is fitted into the central receptacle 11 and two small lamps 12 of extremely low 45 candle power, for instance of 4 candle power are fitted into candelabra receptacles 13, for purposes hereinafter described.

Attention is called to the position of the large lamp, which is so placed that the surface brightness of the enclosing globe is substantially even, when the large lamp is illuminated, while the position of the two auxiliary lamps combined with their low intrinsic brilliancy will render the surface

of the globe dimly but evenly lit when the 55 large lamp is not in use and the small lamps are turned on.

The appliance is particularly adapted for the wards or corridors of hospitals because the central lamp will give ample illumination for all general purposes, while at night where general illumination is not required the small candle power lamps will indicate the position of the light sources and furnish a guide to the attendants of the position of 60 the objects around the room. At the same time the patients will be in comparative darkness and undisturbed by the artificial light when the small candle power lamps are burning, as the low brilliancy evenly spread 65 over the surface of the globe can be practically ignored.

Units designed hitherto to serve in this dual capacity have sometimes been provided with a lamp which contains two filaments, 75 but the life of the smaller, more delicate filament is proportionately shortened because of its being subject to extreme heat while the larger lamp is burning. In cases where resistance is employed to effect a dimming 80 of the lamp other drawbacks are encountered.

The appliance shown in the drawing is the result of considerable study to meet the particular requirements. This fixture has a 85 smooth flaring canopy, globe holder and stem all designed to minimize the collection of dust and to facilitate cleaning. The bottom plate on the socket cover renders it dust-proof as well. The socket holder is designed 90 to support the sockets and lamp in the correct position to obtain the desired results in distribution and intensity. The low intensity lamps are located in the socket holder which is constructed to eliminate shadows 95 or distortion from the globe when the normal or low intensity lights are illuminated. Although the secondary sources are in the position shown the various light rays appear to come from a single source inside the globe. 100

It will be noted that the diffusing globe extends above and below the lamp, that it is of the shape to direct light both upwardly and downwardly so as to illuminate the entire room, and that no shadows will be produced on the ceiling.

I claim:

1. A lighting fixture comprising a canopy,

stem, holder and diffusing globe, the stem being provided with an extension stem extending into the globe and fitted with a socket cover constructed to contain a plurality of receptacles and adapted to contain lamps of various sizes to secure even illumination of different degrees and substantially even surface brightness when the different lamps are illuminated, the diffusing globe 15 extending above and below the lamps so as to direct light upwardly and downwardly.

2. A lighting fixture for hospitals comprising a smooth canopy, stem, holder and diffusing globe, the stem being provided

with a smooth extension stem extending into the globe and fitted with a smooth socket cover constructed to contain a plurality of receptacles and adapted to contain lamps of various sizes to secure even illumination of different degrees and substantially even surface brightness when the different lamps are illuminated, the diffusing globe extending above and below the lamps so as to direct light upwardly and downwardly. 20

Signed at Boston, in the county of Suffolk 25 and State of Massachusetts, this 13th day of July, 1923.

WILLARD W. THOMPSON.
